UNITED STATES PATENT OFFICE.

BERNHARD JOTZEN, OF BARMEN, GERMANY.

METHOD OF MANUFACTURING KEYS FOR KEYBOARDS FOR PIANOS AND LIKE MUSICAL INSTRUMENTS.

Application filed March 31, 1917. Serial No. 159,051.

(GRANTED UNDER THE PROVISIONS OF THE ACT OF MARCH 3, 1921, 41 STAT. L., 1313.)

To all whom it may concern:

Be it known that I, BERNHARD JOTZEN, a citizen of Germany, and resident of Barmen, Rhenish Prussia, Germany, have 5 invented a certain new and useful Improvement in Methods of Manufacturing Keys for Keyboards for Pianos and Like Musical Instruments (for which I have obtained a patent in Germany, No. 296,120, filed Apr. 10 4, 1916, ausgegeben Jan. 13, 1917), of which the following is a specification.

The subject of this invention is a new process of manufacturing keys for keyboards for pianos and like musical instruments. The essential feature of my invention consists on the one hand in the employment of rotary circular saws in order to obtain smooth and exact lateral faces on the keys and on the other hand in 15 the provision of gaging implements for securing the exact position of the saw cuts and also the proper angle of the keys.

My invention will be more fully understood by means of the accompanying drawings in which:

Fig. 1 is a side view of the board or plate from which the keys are cut out,

Fig. 2 is an end view of a pair of circular saws employed in my improved process,

Fig. 3 is a top view of Fig. 1,

Fig. 4 is a longitudinal section through the plate and its support showing the adjustment of the plate while cutting the slanted rear parts of the keys.

Fig. 5 is a top view of Fig. 4, and

Figs. 6 to 8 are detailed views of an implement for treating the corners of the upper keys.

Like letters of reference indicate like parts throughout the drawings.

I intend to manufacture the keys, the shape and formation of which is the usual, by the aid of rotary circular saws instead of band saws hitherto used, thereby obtaining the great advantage that a perfect, smooth cutting surface is earned which needs no further or finishing work. In carrying out my invention I use a wooden board or plate *a* from which the keys are 45 to be cut out. This plate is on its rear part provided with a transverse bar *b* upon which is later mounted the action, its front part being covered with a layer *c* of ivory or other suitable material forming the play-

ing surface. Into said plate *a* are first of 55 all drilled the perforations *d*, which on inserting the keyboard in the piano receive the adjusting pins for the keys. Then the upper or black keys are cut on both longitudinal sides as at *g*, *g*. This is done by 60 means of two rotary circular saws *e*, *f* mounted on a common spindle in a position which corresponds exactly with the breadth of the said keys. The cutting operation takes place from below, the bracket *e*¹ of 65 said saws being slidably guided in a suitable standard *e*² and raised and lowered by a lever *e*³ connected to a treadle lever not shown. The board or plate *a* is secured in its position relative to the pair of saws 70 by means of pins not shown fastened to the support of the plate and engaging the perforations *d*. Of course the plate *a* must be brought in another position by the operator for each fresh double cut. Fig. 1 shows 75 the saws in their uppermost cutting position, while in Fig. 2 the hatched parts illustrate the upper or black keys obtained by the said saws.

The lower or white keys are engendered 80 by the cutting lines *h* which extend from the front edge of the plate *a* partly to the forward ends of the upper keys, partly to the line I—I where the slanted or inclined rear parts of the keys commence and the 85 ivory layer *c* ends. Said cuts *h* are made by the aid of a single circular saw, not shown, in a usual manner.

Hereupon the rear part of the board or plate *a* is separated by cuts *g* running in 90 an inclined direction to the cuts *g*, *g* and *h*, thereby forming the rear slanted parts of the keys. To this end the board or plate *a* is placed on a slide *i* which in any known manner can be travelled on the table *i*¹ of the 95 circular saw *i*². Said slide carries a gaging implement consisting of a plate *n* fulcrumed to a pintle *k* round which said plate is turnable. The plate *n* has an upright tongue *m* which engages one of the cuts or 100 slots *g*, *g*. Spaced apart from said gaging implement is arranged a second one comprising a tongue *o* which is adjustable and can be fixed by a screw *p*, said tongue *o* 105 engaging into one of the cuts *g*. By means of both tongues *m* and *o* the inclined direction of the cuts *g* which form the lateral faces of the rear parts of the keys can be

adjusted. After one cut *q* is made the tongues become operative and they now secure the proper angle of the rear slanted parts of the keys relative to the front parts thereof. The operator before each fresh cut has only to put the plate *a* forward about the breadth of a key as will be easily understood from Fig. 5, the cuts *q* thereby running exactly into the straight cuts *g*, *g* and *h*. It needs now only to cut out the upper or black keys at its forward end or at its front corners. For this purpose a scroll-saw is employed the saw blade of which is shown in Figs. 6 to 8. The novel feature of that saw consists in that the lower part *u* of the blade stands at a right angle to the upper part *v*. Each corner *s* of the upper key is first treated by the part *u* and then by the part *v* as shown in dotted lines in Fig. 7, thereby cutting out the upper keys completely.

It will be obvious from the above description that by my improved method a quick manufacture of keys for keyboards is obtained whereby smooth and exactly cut lateral faces are earned which need no finishing work except polishing.

Claims.

1. The improved method of manufacturing keys for keyboards for pianos and like musical instruments which consists in providing a wooden board or plate first, by means of a double rotary circular saw, at its front part with double parallel cuts forming the side faces of the upper keys, then, by the aid of a single rotary circular saw, also at its front part with cuts running parallel to the double cuts and forming the side faces of the lower keys, thereupon dividing the rear part of the plate, also with the aid of a rotary circular saw, by cuts running into the cuts on the front part but in an inclined direction relative to the said cuts, the exact position and direction of the cuts in the rear part of the plate being secured by means of adjustable gaging tongues arranged on the plate support and engaging the cuts in the plate, and last, by means of a scroll-saw with a blade the lower part of which stands at a right angle to the upper part, cutting out the front corners of the upper keys.

2. The improved method of manufacturing keys for keyboards for pianos and like musical instruments which consists in pro-

viding a wooden board or plate first of all with perforations, then, by means of a double rotary circular saw, at its front part with double parallel cuts forming the side faces of the upper keys, the exact position of the cuts being secured by pins provided on the plate support and engaging the perforations in the plate, then, by the aid of a single rotary circular saw, also at the front part of the plate with cuts running parallel to the double cuts and forming the side faces of the lower keys, thereupon dividing the rear part of the plate, also with the aid of a rotary circular saw, by cuts running into the cuts on the front part but in an inclined direction relative to said cuts, and last, by means of a scroll-saw with a blade the lower part of which stands a right angle to the upper part, cutting out the front corners of the upper keys.

3. The improved method of manufacturing keys for keyboards for pianos and like musical instruments which consists in providing a wooden board or plate first, by means of a double rotary circular saw, at its front part with double parallel cuts forming the side faces of the upper keys, then, by the aid of a single rotary circular saw, also at its front part with cuts running parallel to the double cuts and forming the side faces of the lower keys, thereupon dividing the rear part of the plate, also with the aid of a rotary circular saw, by cuts running into the cuts on the front part but in an inclined direction relative to the said cuts, the exact position and direction of the cuts in the rear part of the plate being secured by means of adjustable gaging tongues arranged on the plate support and engaging the cuts in the plate, and last, by means of a scroll-saw with a blade the lower part of which stands at a right angle to the upper part, cutting out the front corners of the upper keys.

In testimony whereof, I have signed my name to this specification in the presence of two subscribing witnesses.

BERNHARD JOTSEN.
